UNITED STATES PATENT OFFICE.

JOHN F. McFERRAN, OF EVANSVILLE, INDIANA.

STOP MECHANISM.

1,179,854.

Specification of Letters Patent. Patented Apr. 18, 1916

Application filed October 22, 1915. Serial No. 57,318.

To all whom it may concern:

Be it known that I, JOHN F. McFERRAN, a citizen of the United States, residing at Evansville, in the county of Vanderburg and 5 State of Indiana, have invented certain new and useful Improvements in Stop Mechanism; and I do hereby declare the following to be a full, clear, and exact description of the invention, such as will enable others 10 skilled in the art to which it appertains to make and use the same.

This invention relates to mechanism for operating the stop valves of steam engines and other motors from a distance; and it 15 consists in the novel construction and combination of the parts hereinafter fully described and claimed.

In the drawings, Figure 1 is a side view of a stop mechanism constructed according 20 to this invention. Fig. 2 is a plan view of a portion of the same.

The stop valve or regulating valve 2 of the engine is of any approved construction provided with a revolute spindle 3 for operating it. A chain 4 or other similar flexible connection is attached to and wound upon the spindle 3 or upon a wheel or disk secured on the spindle, and a weight 6 is connected to the free end of the chain. This 30 weight 6 slides vertically in a pipe 7 or other similar tubular support which is secured in the engine room. A trigger 8 is provided and is adapted to rest crosswise on the top of the tubular support 7 and engage with the 35 chain 4.

The chain and weight are provided with a ring 10 or other suitable means for engaging very loosely with the middle part of the trigger so that the weight is normally 40 supported by the trigger and the trigger has a curved portion 12 at one end which rests on the edge of the support at one side of the tube. The other end of the trigger has a projecting handle and a stop 14, and 45 the stop 14 engages with the opposite side of the tube and rests on it so that the curved end does not slide off the support. A wire

or cord 15 is connected to the trigger handle 16 which projects beyond the support, and this wire is attached to one arm of a bell- 50 crank lever 17.

The bell-crank lever is pivoted by a pin 18 to a bracket 19 secured to the wall 20 of the engine room. A wire or cord 21 is attached to the other arm of the bell-crank 55 lever and passes through a hole in the wall and is supported inside the mill room or workshop by brackets 22 secured to the floor joists or in any other convenient way. This wire 21 is provided with handles 23 at any 60 convenient points of its length.

When the bell-crank lever is moved by one of the handles in the direction of the arrow in Figure 1, the projecting handle of the trigger is raised so that its curved end 65 portion slides off the support and releases the weight. The descending weight revolves the valve spindle so as to close the valve and stop the engine. The chain is rewound on the valve spindle by means of a hand wheel 70 secured on the valve spindle.

Any other approved means may be used for operating the trigger from a distance besides the wires and bell-crank lever hereinbefore described. 75

What I claim is:

In a stop mechanism, a valve, a flexible connection for operating the valve, a stationary support, a weight secured to the flexible connection, and a trigger normally 80 engaged with the said flexible connection and having the weight suspended from its middle part and having its end portions engaging with the said support on opposite sides of the weight, one of the said end portions being curved upwardly, and means for 85 releasing the trigger connected to its other end portion so that the trigger is operated by the weight when released from the support. 90

In testimony whereof I have affixed my signature.

JOHN F. McFERRAN.
